UNITED STATES PATENT OFFICE.

JOHN B. DENNIS, OF OTTUMWA, IOWA.

SELECTOR APPARATUS FOR CHECKWRITERS.

1,187,274.

Specification of Letters Patent. Patented June 13, 1916.

Application filed January 27, 1916. Serial No. 74,722.

To all whom it may concern:

Be it known that I, JOHN B. DENNIS, a citizen of the United States, residing at Ottumwa, in the county of Wapello and State 5 of Iowa, have invented certain new and useful Improvements in Selector Apparatus for Checkwriters; and I do hereby declare the following to be a full, clear, and exact description of the invention, such as will enable others skilled in the art to which it 10 pertains to make and use the same, reference being had to the accompanying drawings, and to the letters and figures of reference marked thereon, which form a part of 15 this specification.

This invention relates to new and useful improvements in selectors for checkwriters and consists in the provision of a simple and efficient device of this nature, designed especially for use upon a swinging lever type of 20 checkwriter, and the object in view is to generally simplify the mechanism, making it possible to operate the checkwriter accurately without the usual care necessary to 25 the nicety of adjustment of the lever before its operation.

My invention consists of a simple and efficient device of this nature having various 30 details of construction, combinations and arrangements of parts which will be herein-after fully described, shown in the accompanying drawings and then specifically defined in the appended claims.

My invention is illustrated in the accompanying drawings, in which:—

Figure 1 is a front elevation. Fig. 2 is a top plan. Fig. 3 is a side elevation with portions broken away. Fig. 4 is a horizontal section through Fig. 3, looking down, 40 the section being taken just above the arms O, parts being omitted.

Reference now being had to the details of the drawings by letter, A designates the casing of the writer, known to the trade as the 45 "Peerless" and of the general type to which my improvements apply, said frame having a notched segment B adapted to receive an operating lever D which, when depressed, actuates the printing mechanism, but which 50 latter forms no part of the present application.

The operating lever D is pivoted to a projection E³ on the casing F⁴ containing the operating mechanism for check printing, of 55 the usual form. It is mounted on the post E. F is a casing mounted on the post E above

the casing F⁴ and containing the spring E⁴, see Fig. 4, and within which the latter is mounted, one end being fastened to the casing and the other to the post, the latter being provided with a ratchet G, which may be wound by the handle H in order to regulate the tension of the spring. This ratchet is disposed outside the casing F and above the same, as seen in Figs. 1, 2, 3 and 4. A 60 pawl, designated by letter I, is mounted upon an integral arm of the key rack J and is adapted to engage the teeth of the ratchet wheel to hold the latter in different adjusted positions. Said spring tends to normally throw the lever to its farthest limit to 65 the right when the lever comes in contact with the plate N.

O are arms each having one end riveted to the drum casing F, as seen in Fig. 2, see 70 also Fig. 4, the other ends projecting from the key rack, said rack in the present instance being hollow and provided with top and bottom walls which have registering apertures, and depressible keys, designated 75 by letter Q, have stems which are mounted in various registering apertures and are held at their upper limits through the medium of the coiled springs R bearing between 80 the walls of the rack. The stems of said levers are adapted to form stops, when depressed in the path of the lever. Each notch in the segment, before referred to, is represented by a key designating the different 85 numerals and markings to be printed upon 90 the check.

In operation, assuming that it may be desired to print, for instance, a check aggregating \$9957.82, it will be necessary to swing the lever to the left of the button marked 95 90, after which depress the 90 key, release 90, after which depress the 90 key, release 100 the lever and allow the spring to throw the latter back against the stem of the key 90, which will form a stop, then depress the lever and "Ninety" will be printed, it being 105 impossible to carelessly print any other word when the lever is in contact with the stem of the key 90. This being done, the operator then presses key 9, after which the lever is released and allowed to be swung 110 to the right through the influence of the spring which actuates the same, and the lever will be stopped by the stem of the key 9. The lever is then depressed again to depress 9, after which the lever is swung to the left 110 by the key indicating "Hundred", released and allowed to swing back against the stem

of the hundred key, depressed and the word "Hundred" is printed, after which the key 50 is depressed, the lever allowed to swing against its stem, depressed and "Fifty" is 5 printed. Then key 7 is depressed, the lever being held until the stem of the key is in its path, then released, allowing the stem of the key to form a stop. The lever is then depressed and "Seven" is printed. The 10 dollars being at the extreme end to the right of the path and no key being necessary because the end of the slot makes a solid stop for it, the lever is released and allowed to swing there and is depressed and the word 15 "Dollars" printed, after which the lever is swung to the left of the key 80, and the key afterward depressed, printing "Eighty", the lever released, then to the 2 key and then to cents. The lever D swings either 20 way and it moves until the pin in the slot stops it.

From the foregoing, it will be understood that a check for an amount up to one cent less than one million may be 25 printed, and all checks to be printed under \$10,000, necessitate the throwing of the lever the requisite number of times to the left, and all checks less than \$100.00 a less number of throws to the left, the spring attached to the lever causing the latter to be thrown each time in its adjusted position to be actuated for printing the particular wording upon the check.

With my improved attachment, mistakes 30 are absolutely impossible in printing the check if the proper key is depressed so that its stem will form a stop, indicating the exact matter to be printed.

What I claim to be new is:—

40 1. A selector apparatus for checkwriters comprising, in combination with a movable spring-pressed lever adapted to actuate checkwriting mechanism, a series of identification keys designating the matter to be printed upon the check and having stems adapted when actuated to form stops to limit the movement of the lever in one direction.

50 2. A selector apparatus for checkwriters comprising, in combination with a swinging, spring-pressed lever adapted to actuate checkwriting mechanism, a series of identification keys designating the matter to be printed upon the check and having stems adapted when actuated to form stops to limit the movement of the lever in one direction.

55 3. A selector apparatus for checkwriters comprising, in combination with a movable, spring-pressed lever adapted to actuate checkwriting mechanism, a series of spring-pressed identification keys provided with stems forming stops adapted when de-

pressed to limit the movement of the lever in one direction.

65

4. A selector apparatus for checkwriters comprising, in combination with the frame, a movable, spring-pressed lever adapted to actuate checkwriting mechanism, a rack mounted upon the frame, a plurality of de- 70 pressible keys having stems mounted for co-operation with said rack and designed to be thrown into the path of the lever to arrest its movement in one direction.

5. A selector apparatus for checkwriters comprising, in combination with the frame, a movable, spring-pressed lever adapted to actuate checkwriting mechanism, a rack mounted in the frame and having registering apertures in the walls thereof, spring- 80 pressed keys having stems movable through said apertures and designed to extend into the path of said lever and when depressed to limit its movement in one direction.

6. A selector apparatus for checkwriters comprising, in combination with a check- 85 writer frame having an upright post, a swinging lever, a drum mounted on said post, a housing for said drum, a spring se- 90 cured at one end to the drum and the other end to the post, means for regulating the tension of the spring, a rack secured to the frame and means secured to said rack and to said housing for the drum, spring-pressed keys carried by the rack and having stems 95 designed to be projected in the path of the lever and when depressed to form stops therefor to limit the movement of the latter in one direction.

7. A selector apparatus for checkwriters comprising in combination with a check- 100 writer frame, a swinging lever, a spring tending to normally throw said lever to its farthest limit to the right, a key rack hav- 105 ing registering openings, and de-pressible keys having stems mounted in registering apertures, said stems forming stops when depressed in the path of the lever.

8. A selector apparatus for checkwriters comprising in combination with a check- 110 writer frame, a swinging lever, a spring tending to normally throw said lever to its farthest limit to the right, a key rack hav- 115 ing registering openings, de-pressible keys having stems mounted in registering apertures, said stems forming stops when de-pressed in the path of the lever, and springs for normally holding said stems at their upper limit.

In testimony whereof I hereunto affix my 120 signature in presence of two witnesses.

JOHN B. DENNIS.
